(57) **CLAIM**

The ornamental design for a dispensing pump head, as shown and described.

DESCRIPTION

FIG. 1 is a perspective view of a dispensing pump head;

FIG. 2 is a front view of the pump of FIG. 1;

FIG. 3 is a right side view of the pump of FIG. 1;

FIG. 4 is a back view of the pump of FIG. 1;

FIG. 5 is a left side view of the pump of FIG. 1;

FIG. 6 is a top view of the pump of FIG. 1; and,

FIG. 7 is a bottom view of the pump of FIG. 1.

In the drawings, the broken lines show portions of a pump dispensing head that form no part of the claim.
